[57] **CLAIM**

The ornamental design for a combination wrist watch and remote actuator, as shown and described.

DESCRIPTION

FIG. 1 is a perspective view of a combination wrist watch and remote actuator showing my new design;

FIG. 2 is a front plan view thereof;

FIG. 3 is a rear plan view thereof;

FIG. 4 is a bottom view thereof, the top view being a mirror image thereof;

FIG. 5 is a right side view thereof; and,

FIG. 6 is a left side view thereof.

The broken line showing of a portion of a watch strap is for illustrative purposes only and forms no part of the claimed design.
